HIGH CHAIR AND TIE FOR REENFORCING RODS

Bingham F. Burner, Arlington, Va.

Application November 13, 1945, Serial No. 628,026

16 Claims. (Cl. 72—122)

1

This invention relates generally to the class of masonry and concrete construction and the present invention is directed particularly to improvements in that type of reenforcing rod supporting chair known as a high chair.

A principal object of the present invention is to provide a high chair support for concrete reinforcing rods wherein co-acting and relatively movable elements are provided for clamping a pair of crossed rods firmly in working position, with novel means for stiffening or imparting rigidity to the legs of the chair whereby a relatively light material may be employed without sacrificing needed strength.

Another object of the invention is to provide a reenforcing rod supporting chair having a novel means in the form of a pair of relatively movable co-acting hanger elements, for supporting and securing firmly in crossed working relation a pair of reenforcing rods, wherein such cooperating elements are designed in a novel manner to automatically maintain a desired centering relation one with respect to the other so that no difficulty will be experienced in setting the rods in working position.

Still another object of the invention is to provide a novel chair support and clamping means for crossed concrete reenforcing rods, wherein a pair of relatively movable cooperating hanger elements are provided for securing the rods in the stated crossed relation, which have a relatively wide degree of movement, making the device adaptable to a relatively wide range of sizes in reenforcing rods.

Still another object of the invention is to provide a high chair type reenforcing rod support with means for ganging a number of the chairs together in one unit and for, at the same time, shortening the effective flexibility of the legs of the chairs whereby an effective and useful gripping action upon the supported rods may be obtained without the necessity of using unnecessarily heavy material.

Other objects and advantages of the present invention will become apparent as the description of the same proceeds and the invention will be best understood from a consideration of the following detailed description taken in connection with the accompanying drawings forming a part of the specification, with the understanding, however, that the invention is not confined to a strict conformity with the showing of the drawings but may be changed or modified so long as such changes or modifications mark no ma-

2

terial departure from the salient features of the invention as expressed in the appended claims.

In the drawings:

Figure 1 is a view in side elevation of a high chair and rod tie constructed in accordance with the present invention.

Figure 2 is an edge view of the structure shown in Figure 1.

Figure 3 is a view in top plan of the structure as illustrated in Figure 1.

Figure 4 is a view in top plan of the upper part of the chair showing the positions of the knees before the rods are inserted.

Figure 5 is a view in side elevation of a modified construction in which the reenforcing tie rod forms the sole connection between the sides of the legs.

Figure 6 is a view of the structure shown in Figure 5, looking at the same in a direction at right angles to the side shown in Figure 5.

Figure 7 illustrates a method of ganging the chairs by means of a connecting rod.

Figure 8 is a sectional view taken on the line 8—8 of Figure 7.

Figure 9 is a view illustrating another method of connecting a reenforcing rod with the lower end portion of a leg.

Figure 10 is an edge view of the structure of Figure 9.

Figure 11 illustrates another method of forming the bridging connection between the sides of the leg.

Figure 12 is a section on the line 12—12 of Figure 11.

Figure 13 illustrates still another method of forming the connection between the lower ends of the sides of a leg.

Figure 14 is a section on the line 14—14 of Figure 13.

Figure 15 illustrates in side elevation a further embodiment of the invention in which the chair is formed initially in two parts adapted to be assembled and welded together.

Figure 16 is a horizontal section taken substantially on the line 16—16 of Figure 15.

Figure 17 is a view in perspective of one of the two portions of the chair illustrated in Figure 15.

Figure 18 is a view in side elevation of another embodiment in which the two chair portions are joined together by a coil spring.

Referring now more particularly to the drawings it will be seen that the chair tie device as illustrated is formed of a single length or piece of material, preferably low grade spring steel wire and while it is preferred to form the device

in this manner it is to be understood, nevertheless, that the invention is not limited to this specific manner of forming the chair and that a chair formed of several individual pieces welded or otherwise joined together would fall within the scope of the present invention.

Furthermore, it is to be understood that the size of the wire material used, the degree of spring clamping action and the size of the loops and length of the legs of the formed chair, would be governed by the particular type of concrete construction in which the chairs are used and the size of the bars or rods which the chair must support. One feature, however, of the present invention has to do with the reenforcing or stiffening of the legs of the chair when the same is constructed to function as a high chair, in which case, it will be understood that the legs will be of substantial length so as to support the rods at the necessary elevations for which high types of chairs are required.

As shown the chair comprises two side portions each of which is generally designated 10 and may be referred to as a leg. Each of the legs comprises a relatively long side bar or member 11 and an intervening yoke 12, connecting or joining the side bars together at their lower ends.

The yoke 12 as illustrated in Figures 1 to 3, comprises a transverse portion 13 which is elevated a substantial distance above the lower ends of the bars 11 and which merges at each end with the down-turned portion 14 which lies against or closely adjacent to the insides of a side bar or portion 11, merging with the latter at its lower end as illustrated.

Preferably, though not necessarily, the side bars 11 of each leg lean together or are convergent at their top ends as shown in Figure 1 and the two legs also incline together or are convergent at their upper ends as shown in Figure 2, which arrangement, together with the convergent tendency of the two side bars 11 of each leg, has the effect of causing the hereinafter described rod supporting and gripping portions of the chair to press more firmly together under the weight of the rods or with the application of increasing weight to the rods.

The upper ends of the side portions or bars of the two legs together define a hollow quadrangle or, more accurately, the corners of such a figure.

As will be seen upon reference to Figure 3, where the chair is shown in top plan, two adjacent side bars 11 of the two legs come closer together at their upper ends than do the corresponding adjacent side bars 11 so that such upper ends may work in between the upper ends of the opposite bars as will be hereinafter more fully described.

The more closely positioned bars of the two legs are bent to extend downwardly and inwardly toward the center of the structure at 11' and from these bends there extend the short inwardly directed portions 15 which, in addition to extending downwardly toward the center of the chair, are slightly convergent as shown.

At their lower ends, the portions 11' merge with the slightly reversely bent portions forming rod contacting or engaging knees 16 and each of these knees merges into the upper end of a side member or leg 17 of the rod receiving saddle loop which is generally designated 18. The lower ends of these side portions 11' of this saddle loop are connected by the substantially semi-circular bottom part or yoke 19.

The two leg bars 11 opposite from the saddle loop 18 are bent downwardly and inwardly at their upper ends as indicated at 11'' and they then extend into the short downwardly and inwardly extending portions 15' which are slightly convergent and which are reversely bent at their lower ends to form the reenforcing rod engaging knees 16' which co-act with the knees 16. These knee portions lead into or are joined to the upper ends of the legs 17' of a saddle yoke 18' which is a substantial duplicate of the yoke 18 and which has the lower ends of the legs 17' joined by the substantially semi-circular loop 19'.

As will be readily seen upon reference to Figure 1 each of the saddle loops is of substantial length and while being suspended from the inwardly and downwardly extending portions 15-15', which form continuations of the leg side bars 11, they also are disposed in downwardly divergent relation.

The knees 16 at the upper end of the saddle loop 18 are so spaced that the over-all width of the loop at the upper end is not greater than the inside width of the upper end of the loop 18' between the knees 16'. Thus when the upper ends of the saddle loops come together the narrower one will center in the upper end of the wider one as shown in Figure 4. Thus the upper ends of the two parts of the chair will always be in such a position with respect one to the other that a rod when laid in place to be forced down between the knees as illustrated in Figure 1, after the first or lower rod has been positioned, can be readily inserted merely by applying down pressure thereto.

In the construction of high chairs according to the present invention, unless relatively heavy material is used, the bars 11 of the legs tend to have too great flexibility as previously pointed out. This flexibility may be controlled without the necessity of having to use extra heavy material, by means of the brace yoke 12 between the leg bars or a tie rod 20 may be disposed across the outer sides of the bars 11 of each of the legs and welded to the bars in the manner illustrated. Such rod 20 may be of short length or it may be of substantial length and employed for joining or connecting together a number of the chairs to provide a set gang. As will be readily apparent the height at which the rod 20 is placed against the legs 10 will determine the degree of flexibility and relative movement which can be obtained between the cooperating knees 16-16' of the suspension loops. In the construction here illustrated the rod 20 is shown as being disposed at an elevation just above the top of the part 13 of the bracing yoke and if the yoke portion 12 is set substantially vertically instead of in an inclined plane parallel with the bars 11 of the leg, the connecting bar 20 may be placed directly upon the top of the yoke as will be readily apparent.

Another method of stiffening the brace between the two bars 11 of a leg is illustrated in Figure 11 where a transverse or connecting portion 13' of the yoke has the opposite side faces flattened as indicated at 21. These flattened side faces are disposed vertically and thus any tendency of the part 13' to bend up or down will be more greatly resisted than if the rod is left circular as in the arrangement shown in Figure 1.

In the case of a low chair provision may be made for decreasing the resistance to up or down bending of the connecting parts between the lower ends of the leg bars so that by bringing

pered to conform to the inclination of the bars. When the bar members of the legs are disposed at the proper inclination against the outer side of the ring, the members are welded to the ring as indicated at 39. This hook-up or connection between the leg members by means of the coiled-wire ring allows for relative movement between the leg members thereby allowing the saddle loops to be moved apart as necessary for the insertion of a rod therebetween and at the same time sufficient rigidity is given to the leg member to allow for the construction of such members from material of lighter construction than would be possible if the leg members were connected together at their bottom ends or at the surface of the form on which the chair is stood.

I claim:

1. A chair tie for supporting crossed rods, comprising a pair of leg units each having upstanding side portions spaced apart at their upper ends for the passage of a rod therebetween, a pair of saddle loop members suspended between the upper ends of adjacent side portions of the leg members, each saddle loop member having an open upper end for the reception of a rod, and one loop member having its open end of greater width than the open end of the other loop member whereby the open end of the said one loop member receives the open end of the other loop member.

2. A rod chair tie for supporting crossed rods, comprising a pair of leg units each having upstanding side portions convergently disposed toward the upper ends but spaced for the passage of a rod therebetween, a pair of saddle loop members each suspended between the upper ends of two adjacent leg side portions, each saddle loop member having a depth at least as great as the sum of the diameters of two rods and each loop member being open at its top for the reception of a rod, the loop members being formed to provide co-acting opposing knees adapted to engage opposite sides of the top one of the crossed rods, and the knees of one loop member being arranged to enter between the knees of the other loop member.

3. A chair for supporting at least two crossed rods, comprising a pair of suspension members each having the form of a loop open at one end and having a length at least as great as the sum of the diameters of the two rods, means for supporting said loops in adjacent spaced relation to receive and support a rod between them, said means being of a yieldable character whereby the opposite sides of the open ends of the suspension members may have relative movement and the open end of one suspension member may have movement relative to the other member, a knee-like gripping means at the open end of each member cooperating with the gripping means of the other member by a relative movement of the members to bear upon the top of a rod disposed across the first rod, and the open end of one loop member having a width sufficient to receive the open end of the other loop member when the said ends of the members are moved together.

4. A chair support for crossed concrete reinforcing rods, comprising a pair of leg units each having upstanding side portions convergently related and spaced apart at their upper ends for the passage of a rod therebetween, each of said leg side portions merging with a short inwardly and downwardly directed member, a pair of relatively long, substantially U-shaped saddle loop members each disposed between adjacent side

portions of the two leg units and each merging at its upper end with one of the inwardly and downwardly directed members, the upper end of each side of each saddle loop member being bowed to form a rod contacting knee, the said side portions of the leg members being of resilient character and resiliently biased toward the adjacent side portion whereby the said knees of one saddle loop member are urged toward the knees of the adjacent saddle loop member, and the knees of one saddle loop member being spaced apart sufficiently to receive the knees of the adjacent saddle loop member therebetween.

5. A rod chair tie for supporting crossed concrete reenforcing rods, as stated in claim 4, wherein in the said leg units are in upwardly converging relation and wherein the said saddle loop members are disposed in downwardly diverging relation.

6. A rod chair tie for supporting crossed concrete reenforcing rods, as stated in claim 4, with a rod disposed transversely of each leg unit and connected with the stated upstanding side portions thereof at an elevation a substantial height above the bottom of the unit and functioning to restrict the flexibility of the said side portions to the parts thereof between such bar and the top ends of the portions.

7. In a rod chair tie for supporting crossed concrete reenforcing rods, a pair of leg units each comprising two upstanding, upwardly converging side portions, means supported between the side portions of one unit and the corresponding side portions of the adjacent unit for the support of crossed reenforcing rods, said leg side portions merging at their lower ends with a transversely extending intermediate connecting portion functioning to maintain said leg side portions in spaced relation, and said connecting portion being formed to have a greater dimension in one direction than in the other whereby to stiffen such portion against bending in one direction.

8. A supporting chair for concrete reenforcing rods, comprising four leg members arranged in upwardly convergent relation, a pair of rod receiving hanger loops each forming an integral continuation of the upper ends of two leg members and hanging between such members in opposed relation to receive and support a rod, the upper ends of the sides of each loop being bent toward the corresponding sides of the opposed loop to form rod gripping knees, the knees of each loop being spaced apart to permit a rod to be passed therebetween and the knees of one loop being sufficiently spaced to receive between them the spaced knees of the opposing loop, said loops being of a depth greater than the combined diameters of two crossed rods whereby the opposed knees of the loops will bear upon the top one of two crossed rods above the center of the top rod when such rods are arranged with the lower one lying within the loops and the top one lying between the loops, and a connecting means between the leg members beneath the loops.

9. A supporting chair for concrete reenforcing rods as set forth in claim 8, in which the said connecting means between the leg members comprises an annular member lying in a plane perpendicular to the longitudinal axis of the chair and within the area defined by the leg members.

10. A supporting chair for concrete reenforcing rods as set forth in claim 8, in which the said connecting means comprises arched bracing arms extending in crossed relation between diagonally spaced leg members, said arms crossing and being

the lower ends of the bars closer together or moving them farther apart slight adjustments may be made in the height of the rod to be supported by the chair.

Figure 13 illustrates the lower portion of one leg of a low chair, wherein the leg is generally designated 22 and the side bars 23 of which are shown connected by the bottom cross connecting yoke 24 which is initially slightly upwardly bowed. This yoke portion 24 is flattened upon its top and under surfaces so that its width exceeds its vertical thickness and thus it will be readily apparent that the yoke can be more easily bent upwardly or downwardly to alter the distance between the lower ends of the leg bars 23.

In the arrangement shown in Figures 9 and 10 the lower ends of the side bars of the leg are shown as joined with the ends of an upwardly arched yoke which is generally designated 25. In this arrangement the yoke 25, which is substantially U-shaped, has the top part set out from the plane of the leg side bars 26 and the brace rod 27 which is disposed across the bars 26 of the leg and welded thereto, rests upon the top of the yoke 25 at its center and may be welded thereto as illustrated, thus giving a three-point connection and substantially adding to the rigidity of the structure. This rod 27 as in the case of the rod 20, may be a short piece of material functioning only as a connection between the side bars of the leg or it may be a long piece of material functioning to connect together a number of the chairs in a gang.

Still another modification of the stiffening rod feature of the invention is illustrated in Figure 5 where the side bars 28 of the legs are not joined by an integral portion between their lower ends as in the arrangement shown in Figures 1 to 3 but are connected together solely by the coupling rod 29, while a still further modification combining the features of joining the chairs together in a gang and also providing for the stiffening of the bars of the legs, is shown in Figure 7 where a single rod only, designated 30, may be employed, running beneath the saddle loops 18-18' and joined to one thereof in the manner illustrated in my copending application, Serial No. 573,200. With this arrangement only a single rod is required for connecting the chairs together in a gang and the desired stiffening action may be given to the bars of the legs by means of the yoke structure 31, corresponding to the structure illustrated in Figure 1 and designated 12.

From the foregoing it is believed that the manner of using the present chair structure will be readily apparent. It will also be readily apparent that by reason of the interconnecting action of the upper ends of the saddle loops, a wide range of movement between the loops may be obtained so that rods of all sizes may be used in a chair of standard dimensions.

In using the chair structure, after the same has been set up in the desired position, the lower rod, here designated 32, is set into position to rest in the lower ends of the saddle loops, extending between the loops and positioning between the legs 10. The top rod 33 is then placed in position upon the inwardly sloping portions 15-15' and, by the application of the necessary down pressure, forced down between the knees 16-16', the sloping portions upon which it bears, functioning as cams so as to spring the upper ends of the co-acting bars 11 of the legs apart. The length of the saddle loops is such that the top

rod can pass down between the knees of the opposing loops until such knees are at a substantial elevation above the axial center of the rod. Thus it will be seen that the knees will tend to

5 move together along the rounded portion of the rod above the plane of its longitudinal center and thus create a down pressure so as to press the rod firmly down upon the lower rod 32. In this manner the rods are securely or firmly locked together and it will be readily apparent that any additional pressure applied to the top rod as, for example, by some one stepping upon the rod, will only tend to make the gripping action of the chair more positive.

Figures 15 to 17 designate two other methods of coupling together and stiffening or reenforcing the legs of chairs.

In the forms of the invention shown in Figures 1 to 4 the chair structure is illustrated as being 20 formed or bent from a single piece of wire material. In this construction after the single piece of wire has been properly shaped the ends thereof are welded together. This method of forming the chair, while entirely feasible, requires somewhat more complicated mechanism than is required to construct a chair according to either of the two designs shown in Figures 15 to 17.

Figure 15 shows a chair construction in which the two legs are separately formed and are then 30 welded together at the center of the chair. In this form each of the legs is designated 31 and comprises the two side portions 32, each of which corresponds with a side bar or member 11 of the structure shown in Figure 1. However, in this 35 design the suspension yoke here generally designated 18" is carried between the upper ends of the bar members 32.

Extending upwardly and inwardly from the lower end of each side portion or bar member 40 32 is the arched brace arm 33 and these brace arms are in crossed relation as shown.

In setting up a chair with the two leg structures 31, the leg portions of the yokes 18" are 45 brought into opposing relation and the terminal portions of the two arched brace arms 33 of one leg are placed in side by side relation with the corresponding arms of the opposing leg as shown in Figure 16. While being held in this assembled relation the crossed arms of the two legs 50 are welded together at the points 34 or otherwise as may be found most suitable.

With this method of coupling the two leg parts together it is possible to assemble them 55 easily and quickly in exactly the right relation and weld the arched arms together while holding them at the crossing points in a suitable gripping tool. After the arched arms have been welded together it will be seen that the legs will be rigidly braced diagonally across the chair as well as being held against any extreme 60 movement together or apart.

In Figure 18 the chair structure has the two leg portions each of which is generally designated 35, in which the side bars or side members 36 have their lower ends turned outwardly to form 65 the supporting feet 37. In this form of the invention also each leg member supports the rod receiving yoke 18"" between the side members 36.

In the design employing the leg units 35 the 70 joining together of two legs is accomplished by the use of a coiled wire ring generally designated 38.

As shown the coiled wire ring is placed within 75 the four leg members or bars and is suitably ta-

secured together at the axial center of the chair.

11. In a concrete reenforcing rod supporting chair including four leg members and a pair of rod supporting loops suspended therebetween, re-enforcing connecting means between said leg members comprising arched members arranged in crossed relation beneath said loops and joined at their ends to the leg members.

12. In a concrete reenforcing rod supporting chair including four leg members and a pair of rod supporting loops suspended therebetween, a rigid bracing member extending between two pairs of legs at a substantial elevation above the lower ends of such legs, the said rigid bracing means being joined with the legs between which it is positioned, at the lower ends of the legs.

13. In a concrete reenforcing rod supporting chair including four leg members and a pair of rod supporting loops suspended therebetween, re-enforcing connecting means between said leg members comprising an arcuate arm joined to each leg member and extending upwardly and inwardly therefrom toward the central part of the chair, the said arcuate arms being crossed and rigidly joined together beneath the supporting loops at approximately the axial center of the chair.

14. In a concrete reenforcing rod supporting chair including four leg members and a pair of rod supporting loops suspended therebetween, re-enforcing connecting means between said leg members comprising an annulus disposed in the

area defined by the leg members and in a plane substantially perpendicular to the longitudinal axis of the chair, the annulus contacting each of the leg members and being rigidly coupled thereto.

5 15. In a concrete reenforcing rod supporting chair including four leg members and a pair of rod supporting loops suspended therebetween, re-enforcing means between said leg members

10 comprising an annular member lying in a plane perpendicular to the longitudinal axis of the chair and within the area defined by the leg members, and secured to the leg members.

15 16. In a concrete reenforcing rod supporting chair including two pairs of leg members and a pair of rod supporting loops disposed in adjacent cooperative relation and each suspended by a pair of leg members, reenforcing connecting means between the pairs of leg members comprising a substantially rigid member disposed in a plane perpendicular to the longitudinal axis of the chair and contacting a leg of each pair and rigidly secured thereto.
